COMBINED VENDING AND ADVERTISING DEVICE

Rudolph G. Hourtienne, Pasadena, Calif.

Application March 23, 1933. Serial No. 662,290

6 Claims. (Cl. 46—40)

This invention relates to a toy and vending machine.

The general object of the invention is to provide a toy which includes an improved animated figure.

A further object of the invention is to provide a combined animated figure and vending device wherein the parts are so arranged that when the figure is animated the vending device will be actuated.

Other objects of the invention will be apparent from the following description taken in connection with the accompanying drawings wherein:

Fig. 1 is a fragmentary view partly in elevation showing my invention.

Fig. 2 is a view similar to Figure 1 showing the figure in a different position.

Fig. 3 is a view similar to Figure 1 but taken from the opposite side of the device.

Fig. 4 is a fragmentary elevation partly in section showing details of the feed control and

Fig. 5 is an elevation showing an installation of my invention.

Referring to the drawings by reference characters I have shown my invention as embodied in a device indicated generally at 10. The device as shown includes the case 11 having a bottom 12 and having a transverse partition 13 therein.

Mounted on the partition 13 is a shaft 14. On this shaft I mount a body 15 which is indicated as the body of a horse. This body is preferably made of embossed metal and includes a front leg 16 and a rear leg 17. The front leg 16 includes a pivoted end portion 18 including a hoof 19 which is preferably weighted. The rear leg 17 is provided with a portion 18' which includes a weighted hoof 19'.

The body 15 is also provided with a tail 20 which is pivoted thereon as in 21 and has a neck 22 and head 23 which is pivoted at 23. A rider is indicated at 24 and this rider is mounted on a pivot 25. The arm 26 of the rider is pivoted as at 27 and the hat 28 of the rider is pivoted to the head of the rider as at 29.

The rear leg 17 includes an upstruck flange 30 which is apertured to receive a pair of elongated springs 31. The ends 32 and 33 of the springs are bent as indicated to hold the spring in place. The other end portions of the springs 31 pass through an aperture in a plate 34 on the head and the ends 35 and 36 of the springs are bent to hold the parts assembled in position.

The shaft 14 is provided with a crank 37 which when the shaft is rotated engages the springs 31 and moves them downwardly as shown in Fig. 2.

In this movement the crank 37 first strikes the top of the springs 31 and forces them down thus rocking the entire body of 15 about the shaft. Further movement of the shaft causes the crank to engage with the upper portion of one spring 31 so that the crank wipes across the spring device thus causing a downward movement of the head and causing an abrupt upward movement of the rear foot 17. The movement of the rear foot 17 is sudden and as a result the weighted end 65 portion or hoof 19 moves outwardly and upwardly as shown in Fig. 2.

The spring 31 when operated strikes a second spring 38 which is pivoted at 39 in a bracket 40. The end 41 of this spring when depressed causes 70 the spring to rock and raises the end 42 which passes through the apertured plate 43 on the front leg 16. Thus when the shaft 14 is turned the spring 38 is rocked thus moving the front leg upwardly and causing the front hoof 19 to be 75 thrown forwardly due to the weighted portion 19.

The figure 24 is provided with a spring 49 which has a weight 50 at the lower end thereof and the spring passes through an apertured plate 51 in the hat 28. When the body 15 is moved 80 from the position shown in Fig. 1 the weight member 50 due to the resilience of the spring 49 causes the hat to fly upwardly as shown in Fig. 2. The spring 49 is at one side of the crank 37 so that the crank does not strike the weight 50 or 85 the member 49.

The body 24 includes a lateral member 53 which constitutes a weight which in the position shown in Fig. 2 engages the body 15 to limit the tilting movement of the Fig. 24 relative to the 90 body.

The weight 53 in the position shown in Fig. 2 rocks a lever 54 which is pivoted on 55. This lever passes through an apertured plate 56 on the tail 20 of the horse so that the tail is moved 95 vertically as shown in Fig. 2. The bucking action is limited by a pin 57 mounted on the partition 13. This pin works in a slot 58.

The partition 13 is apertured as at 60 and in line with the aperture 1 I show a plate 61 which 100 is apertured at 62 in line with the aperture 60 as shown in Figure 4. On this plate is mounted a valve member 63. The plate 61 is pivoted as at 64 to the partition 13.

Mounted on partition 13 I provide a chute 65 105 from which a transverse chute 66 extends downwardly and terminates at the aperture 62.

The plate 61 is provided with a weight 67 so that when the valve is free to move the weight causes it to move to the position shown in Fig. 4. 110

A valve control member comprising a pair of adjacent springs is shown at 68. This member 68 is mounted on a bracket 69 which is pivoted as at 70. One portion of the member 68 engages a 5 pin 71 on the partition 13 while the adjacent portion 72 projects in the path of movement of a cam 73 mounted on a disc 74 which is secured to the shaft 14.

The disc 74 has a gear 75 thereon which meshes 10 with a gear 76 mounted on the reduction drive shaft of a motor 77. This motor includes leads 78 and 79 which terminate in a pair of spaced contacts constituting parts of a mercury switch 80 mounted on arm 81 which is pivoted at 82.

15 Arm 81 includes a weighted portion 83 which is mounted in a coin slot 84 and the construction is such when a coin indicated at 85 strikes the member 81 it rocks this member about the pivot 82 so that the member 81 takes the position 20 shown in Fig. 4 and in this position the mercury in the mercury switch 80 bridges the two contacts therein and closes the circuit to the motor 77. A spring 86 holds the arm 81 in each of its extreme positions.

25 Assuming that the parts are in the position shown in Fig. 3 when the coin is inserted it rocks the member 81 thereby starting the motor which rotates the disc 74. As the disc rotates the shaft 14 also rotates, thus causing the crank 37 to 30 rotate to thereby animate the horse and rider.

When the disc rotates to the position shown 35 in Fig. 4 the cam 73 engages and lifts the portion 72 thereby rocking the member 68 so that the end 90 of this member moves downwardly to the position shown in Fig. 4. A stirrup 91 is mounted on the plate 61 and when the member 90 moves downwardly this stirrup is freed so that the valve 63 is moved downwardly by the weight 67 to the position shown in Fig. 4 wherein 40 an article such as a candy ball 93 is released and drops from the aperture 62.

The end 90 of the valve control member includes a portion 94 which engages the articles 95 in the chute 65 until the member 68 is rocked. 45 Before the operation the foremost article 96 of the articles 95 takes the position shown in Fig. 4 and retains this position until the member 73 has rocked the member 68 after which the member 68 moves upwardly and the portion 94 squeezes 50 beneath the lowermost article 97 (Fig. 4) and holds this article in the position shown in Fig. 3. The article 96 is released and passes down the chute 66 to a position adjacent to the aperture 60 which has meanwhile been closed by the valve 63.

55 At the same time this vending occurs a kicking action takes place and at the same time a circuit closure 98 on the disc 74 closes the circuit across two terminals 99 and 100 thereby supplying current to an electric lighted bulb 101. The bulb 101 is arranged in an opaque container 102 which has translucent areas 103 arranged to simulate a lightning flash. Therefore at the period that the candy is vended, the horse kicks, and the flash of lightning occurs to the enjoyment of the purchaser of the candy or other article. To break the circuit to the motor I provide a member 81' arranged in and projecting from the disk. This member 81' engages the end of the arm 81 which is opposite to the weighted portion 83 and rocks the arm 81 so that the circuit through the mercury switch 80 to the motor is broken.

My invention, also, can be used in connection with advertising novelties, for instance, for advertising gasoline the words, "gasoline has a

kick" can be placed just above the animal and arranged to illuminate just as the animal kicks.

From the foregoing description it will be apparent that I have provided a novel combined vending and advertising device which is simple 80 in construction and highly efficient in use.

Having thus described my invention, I claim:

1. In a device of the class described, a body having limbs, a head, a figure and a tail all pivoted thereon, means connecting said limbs, 85 head and tail whereby said device becomes animated, means for actuating the pivoted portions to cause one of the limbs to simulate a kicking action, said means including a shaft, said shaft having a crank thereon, a disc on said shaft, an electric motor, means whereby said motor rotates said shaft, said motor having a circuit including a pair of spaced contacts, means to bridge said contacts to initiate movement of said disc and means on said disc to actuate said bridging 90 means to break the circuit to said motor.

2. In a device of the class described, a body, a front leg pivoted to said body, a rear leg pivoted to said body, a tail pivoted to said body, a neck and head pivoted to said body, a rider pivoted 100 on said body, an arm pivoted on said rider, a hat movable on said rider, means to pivotally support said body, means to cause the forward portion of said body to move downward, means to move the head downwardly, means to move the rear foot upwardly, means to move the front foot upwardly, means to control the forward tilting of said body, means to raise the tail, means to raise the hat and means to move the arm forward. 110

3. In a device of the class described, a body, a front leg pivoted to said body, said front leg including a knee joint, a rear leg pivoted to said body, said rear leg including a knee joint, a tail pivoted to said body, a neck and head pivoted 115 to said body, a rider pivoted on said body, an arm pivoted on said rider, a hat pivoted on said rider, means to pivotally support said body, resilient means operable to cause the forward portion of said body to move downward, said resilient means 120 being connected to said head to move the latter downwardly and connected to the rear leg to move the latter upwardly when the resilient means is moved, means operated by said resilient means to move the front foot upwardly, means to control the forward tilting of said body, means to raise the tail, means to raise the hat and means connecting said arm and said head to move the arm forward when the head is tilted downward. 125

4. In a device of the class described, a body 130 made of embossed metal, a front leg pivoted to said body, said front leg including a weighted foot and a knee joint, a rear leg pivoted to said body, said rear leg including a pivoted knee joint and a weighted foot, a tail pivoted to said body, 135 a neck and head pivoted to said body, a rider pivoted on said body, an arm pivoted on said rider, a hat pivoted on said rider, means to pivotally support said body, a crank on said last mentioned pivot means, resilient means operated 140 by said crank to cause the forward portion of said body to move downward when said crank is operated, said resilient means being connected to said head to move the latter downwardly and connected to the rear leg to move the latter upwardly when the resilient means is moved, means operated by said resilient means to move the front foot upwardly, weighted means to control the forward tilting of said body, means operated 145 by said weighted means to raise the tail, weighted 150

- means connected to said hat to raise the same, means connecting said arm and said head to move the arm forward when the head is tilted downward, a target and means to simultaneously 5 move said target upon the actuation of said device.
5. In a device of the class described, a body having limbs, a head, a figure and a tail all pivoted thereon, means connecting said limbs, head and tail whereby said device becomes animated, 10 means for actuating the pivoted portions, said means including a shaft, said shaft having a crank thereon, a disc on said shaft, an electric motor, means whereby said motor rotates said shaft, said motor having a circuit including a pair of spaced contacts, means to bridge said contacts to initiate movement of said disc, means on said disc to actuate said bridging means to break the circuit to said motor, a target including 15 shaft, said motor having a circuit including a pair of spaced contacts, means to bridge said contacts to initiate movement of said disc, means on said disc to actuate said bridging means to break the circuit to said motor, a target, said 20 target including a pivoted member, said pivoted member being adjacent one of said limbs, means on said disc to move said pivoted target member, the two means on said disc being synchronized whereby said pivoted target member is 25 moved at the time said body is actuated.
6. In a device of the class described, a body having limbs, a head, a figure and a tail all pivoted thereon, means connecting said limbs, head and tail whereby said device becomes animated, means for actuating the pivoted portions to cause 80 one of the limbs to simulate a kicking action, said means including a shaft, said shaft having a crank thereon, a disc on said shaft, an electric motor, means whereby said motor rotates said shaft, said motor having a circuit including a pair of spaced contacts, means to bridge said contacts to initiate movement of said disc, means on said disc to actuate said bridging means to break the circuit to said motor, a target including 85 a pivoted member, said pivoted member being adjacent one of said limbs, means on said disc to move the pivoted member of said target, the two means on said disc being synchronized whereby said pivoted target member is actuated at the time said one limb is moved to simulate 90 a kicking action, and a flash device actuated upon movement of said target.
